UNITED STATES PATENT OFFICE.

STANLEY ROTH AND CLEMENT F. ROMADKA, OF MILWAUKEE, WISCONSIN.

DESIGN FOR A PHONOGRAPH CABINET.

Application filed January 31, 1921. Serial No. 441,493. Term of patent 3½ years.

To all whom it may concern:

Be it known that we, STANLEY ROTH and CLEMENT F. ROMADKA, citizens of the United States, residing at Milwaukee, in the county of Milwaukee and State of Wisconsin, have invented a new and original and ornamental Design for a Phonograph Cabinet, of which the following is a specification, reference being had to the accompanying drawing, forming part hereof.

Fig. 1 is a front elevation of a phonograph cabinet showing our new design;

Fig. 2 is a rear elevation, and
Fig. 3 is a side elevation thereof.

We claim:

The ornamental design for a phonograph cabinet as shown.

CLEMENT F. ROMADKA.
STANLEY ROTH.
